UNITED STATES PATENT OFFICE

2,165,125

ARTICLE OF FURNITURE

William J. Bargen, Waukegan, Ill.

Application April 27, 1937, Serial No. 139,316

14 Claims. (Cl. 155—128)

This invention relates to an article of furniture, more particularly to a combined desk, chair and pedestal structure designed primarily for use in school and lecture rooms, but it is to be understood that it is to be employed in any connection for which it may be found applicable.

The invention has for its object to provide, in a manner as hereinafter set forth, a structure of the type referred to including a chair and a desk capable of being vertically adjusted upwardly, downwardly and angularly relative to the chair independently of the latter, whereby when the structure is to be used it may be so adjusted to afford the maximum amount of comfort to the user.

A further object of the invention is to provide, in a manner as hereinafter set forth, a structure of the type referred to including a combined arm rest and desk element, a chair including a seat and a back and upwardly and downwardly adjustable supporting means for said element connected to said seat and back.

A further object of the invention is to provide, in a manner as hereinafter set forth, a balanced structure of the type referred to which will stay in place when positioned on a floor or other support, whether said structure be anchored or non-anchored to the floor or support.

A further object of the invention is to provide, in a manner as hereinafter set forth, an article of furniture including a chair and desk arranged above the seat of the chair in forwardly extended relation to the latter, said desk and chair having secured therewith coacting means for supporting the desk and to permit of the desk being adjusted upwardly and downwardly, forwardly and rearwardly and angularly with respect to the seat of the chair.

A further object of the invention is to provide, in a manner as hereinafter set forth, a structure including a desk, a seat, a pedestal, a vertically adjusting attachment for the seat possessing resiliency and an adjusting attachment for the desk possessing resiliency.

A further object of the invention is to provide, in a manner as hereinafter set forth, a structure of the class referred to including a chair capable of maintaining its proper balance with respect to a floor or other support regardless of the weight placed thereon or parts connected thereto, whether desk is attached to floor or left loose.

A further object of the invention is to provide, in a manner as hereinafter set forth, a structure of the class referred to including a suspended desk so arranged whereby the increase of

weight thereon does not change the proper balance of the desk with respect to the floor line whether attached to floor or left loose.

A further object of the invention is to provide, in a manner as hereinafter set forth, a structure of the class referred to including a chair which maintains its proper center of gravity and perfect balance with respect to the floor line even after weight is placed thereon or parts attached thereto, whether desk is attached to floor or left loose.

A further object of the invention relates to the new and improved combined desk supporting and adjusting attachment and a coupling and anchoring means for the attachment.

A further object of the invention is to provide, in a manner as hereinafter set forth, a structure of the class referred to including a pedestal for the seat of a chair, said pedestal having a stationary section and a vertically adjustable section, said stationary section including a base merging into a hollow standard slightly off center with respect to the base, said adjustable section including a head for connection to a chair seat and a post in telescopic arrangement with respect to the standard, and said pedestal including means interengaging with the post and standard for detachably locking the adjustable section in adjusted position.

Further objects of the invention are to provide, in a manner as hereinafter set forth, a structure of the class referred to which is comparatively simple in its construction and arrangement, strong, durable, compact, conveniently adjusted when desired, thoroughly efficient for the purpose intended thereby, readily assembled and comparatively inexpensive to manufacture.

To the above ends essentially and to others which may hereinafter appear the invention consists of the novel construction, combination and arrangement of parts as will be more specifically referred to and as illustrated in the accompanying drawings wherein are shown embodiments of the invention, but it is to be understood that changes, variations and modifications may be resorted to which fall within the scope of the invention as claimed.

In the drawings:

Figure 1 is a perspective view of the article of furniture in accordance with this invention,

Figure 2 is a side elevation thereof,

Figure 3 is a fragmentary view in side elevation and lengthwise section showing the supporting and adjusting means for the desk,

 Figure 11 is a fragmentary view in vertical section of the pedestal.
 Figure 12 is a section on line 12—12, Figure 11.
 Figure 13 is a front elevation of the latching member for the vertically adjustable section of the pedestal.
 Figure 14 is a fragmentary view in side elevation of a modified form, showing a combined desk and receptacle.
 Figure 15 is a section on line 15—15, Figure 14.
 Figure 16 is a section on line 16—16, Figures 3 and 14.
 Figure 17 is a section on line 17—17, Figure 14, broken away.
 Figure 18 is a section on line 18—18, Figure 17.
 Figure 19 is an elevation of the clamping block employed in both forms.
 Figure 20 is an inverted view in perspective of the lower end of the carrying, receiving and supporting means for the adjusting member of the desk.
 Figure 21 is a fragmentary view in side elevation of an article of furniture in accordance with this invention including a modified form of adjusting and supporting member for the combined desk and arm rest, a modified form of carrying, receiving and supporting means for the modified form of adjusting member, and a modified form and arrangement of an open top receptacle.
 Figure 22 is a fragmentary view of the modified form of carrying, receiving and supporting means looking towards the upper portion of its inner face.
 Figure 23 is a section on line 23—23, Figure 21.
 Figure 24 is a section on line 24—24, Figure 22.
 Figure 25 is a section on line 25—25, Figure 21.
 Figure 26 is a perspective view of an adjuster of angle contour forming a part of the modified form of the desk adjusting element.
 Figure 27 is an end view of a modified form of a combined desk, arm rest and book box structure.
 Figure 28 is a vertical sectional view of the modified structure shown in Figure 27 with the desk and arm rest elevated, and
 Figure 29 is a section on line 29—29, Figure 11.
 The article of furniture is in the form of a unit or structure including a chair 20 formed of a seat 21 and a back 22, a desk 23 provided with a rearwardly extending arm rest 24, a pedestal 25 having a vertically adjustable upper section and a stationary lower section, an adjusting member or element 26 for desk 23 and a carrying, receiving and supporting structure or means 27 for member 26 which is connected to the seat 21 and back 22.
 The chair 20 is shown by way of example as having the seat thereof disposed at a downward inclination from front to rear and its back formed of a pair of substantially L-shaped oppositely disposed members 28 of angle shape cross section at any point throughout their length and a panel 29 arranged between and extended upwardly from the upstanding parts of the members 28. These latter are also formed with horizontally disposed lower parts which are anchored to the seat 21. The members 28 are arranged at the side edges of the seat 21 and panel 29 and extend against the rear face of the panel and lower face of the seat. The members 28 are secured to and anchor the seat and panel together. The back extends rearwardly at an inclination from the rear end of the seat. The latter and back are disposed in angular relation.
 The desk 23 is formed from a one-piece flat body 30 consisting of a rectangular part 31 and a rearwardly extending flat short narrow extension 32 arranged at the left terminal portion of the rear edge of part 31 when looking towards the structure as shown in Figure 1. The part 31 provides the desk 23 and the extension 32 the arm rest 24.
 The lower stationary section of the pedestal 25 includes a base 33 and a tubular standard 34 open at each end and communicating with the base 33 through the top of the latter. The standard 34 is disposed slightly off center with respect to and is integral with base 33. The rear side 35 of standard 34 is formed centrally with a vertical cutout 36 (Figure 11) which opens at the top edge thereof. The rear side 35 of standard 34 below and in alignment with cutout 36 is formed with a pair of superposed aligned openings 37. The base 33 and standard 34 are of the same form and arrangement as the stationary lower section of the pedestal disclosed in my co-pending application, Serial Number 139,316, filed April 27, 1937. The vertically adjustable upper section of the pedestal 25 includes a tubular post 38 provided at its upper end with a head 39 which is anchored to the lower face of seat 21 eccentrically of the latter. The head 39 will be of the same form as the head of the upper section of the pedestal disclosed in my pending application aforesaid. The post 38 is telescopically arranged in standard 34 and is open at its lower end. The standard 34 and the post 38 are of octagonal contour in transverse cross section (Figure 12), but the cross sectional area of post 38 is materially less than that of standard 34. When post 38 and standard 34 are held in latching or locking relation, by a means to be referred to, that portion of the outer faces of the sides 38^a, 38^b arranged in the standard 34 are in abutting relation with the inner faces of the sides 34^a, 34^b of the standard and the other sides of the post 38 are spaced from the other sides of the standard 34, or in other words, the said other sides of the post are in what may be termed floating relation with respect to the standard. With reference to Figure 12, it will be seen that the binding engagement of the standard and pedestal is had at oppositely disposed angles of 45°. The rear side 40 (Figure 11) of post 38 is formed centrally with a passage 41 extending from the upper to the lower end thereof. The inner face of the said rear side 40 is formed with a pair of vertically extending toothed racks 42 which border the side walls of passage 41. The adjustable upper section of pedestal 25 is detachably secured in its adjusted positioned by a toothed locking element 43 (Figures 11, 12 and 13) coacting with the walls of cutout 36 and the teeth of racks 42. The element 43 is in the form of block 44 provided at its upper end with a pair of oppositely disposed arms 45, 46 extending at right angles to block 44. The arm 46 provides a handle piece and latching member. The forward face of block 44 is squared. The rear face of block 44, lengthwise thereof and at its side marginal portions, is formed with a pair of oppositely disposed elongated rabbets 47, 48, a pair of short rabbets 49, 50

50 spaced from the lower ends of rabbets 47, 48 respectively and a pair of oppositely disposed short rabbets 51, 52 arranged below rabbets 49, 50 respectively and spaced from the lower end of the block. The rabbets 47, 49 and 51 align. The rabbets 48, 50 and 52 align. The rabbets 47 and 48, the rabbets 49 and 50, and the rabbets 51 and 52 provide the rear face of block 44 respectively, with an elongated rib 53, a short rib 54 and a short rib 55. The ribs are arranged in spaced alignment. The rabbets 47, 49 and 51 form the rear face of block 44 with a set of teeth 56 for coaction with one of the racks 42. The rabbets 48, 50 and 52 form the rear face of block 44 with a set of teeth 57 aligning in spaced relation with the teeth 56 and for coaction with the other rack 42. The engagement of the sets of teeth 56, 57 with selected teeth of the racks 42 provides a floating joint for holding the post 35 in its desired adjusted position. To prevent block 44 turning relative to post 35, the arm 45 extends through passage 41 and the arm 46 is positioned in cutout 36. To prevent the shifting of element 43 with respect to standard 34 and post 38 and for releasably maintaining the sides 38^a, 38^b of post 38 in binding engagement with the sides 34^a, 34^b of standard 34, the element 43 is formed with a pair of superposed aligned threaded openings 58, the walls of which are adapted to be engaged by a pair of headed threaded locking bolts 59 extending through openings 37 and engaging in the openings 58. Lock washers 60 are provided for the bolts 59.

The adjusting member 26 (Figures 1, 2 and 3 to 10) includes a horizontally disposed head 61 and a hollow shank 62 closed at its top, open at its bottom and having its inner side formed, lengthwise thereof, with a slot opening at its lower end. The specific construction of shank 62 will be hereinafter set forth. Shank 62 depends from and is disposed at a rearward inclination with respect to head 61. The latter extends at a slight upward inclination from rear to front and includes a forward part 63 having a downwardly curved rear portion 64. The part 63 in vertical section at any point throughout its length is of angle-shaped contour forming a pair of flanges 65, 66 disposed at right angles to each other. The head 61 includes a rear part 67 having an inwardly flanged upstanding web 68 merging at the rear end of its top into a rearwardly extending flat apertured arm 69. The lower portion of the front of the top of web 68 merges into the lower part of the rear portion 64 of part 63. That part of the top of the web 68 above the point of emergence of the web 68 with the lower part of the rear portion of part 63 is spaced from the upper part of the rear portion 64 of part 63 to provide a gullet 70. The shank 62 is integral at its upper end with the flanged web 68 and includes a front wall 71, an inclined top wall 72 formed at its inner side with an inwardly extending flange 74, and a pair of side walls 75, 76 formed at their inner sides with inwardly extending flanges 77, 78 respectively. The upper ends of the flanges 77, 78 merge into the end portions of the flange 74. The flanges 77, 78 have their lower ends arranged above the lower ends of the walls 75, 76. The manner of setting up the shank 62 provides its rear or inner side with an opening or slot. The wall 71 in proximity to its lower end is formed with a pair of screw threaded aligned openings 79. The adjusting member 26 at its upper end and in alignment with its shank has the front of part 67 of its

head 61 formed with a pair of oppositely extending aligned arms 80, 81 having slots 82 in their outer ends. The arms 80, 81 are disposed at right angles to head 61. The arm 80 is of greater length than arm 81 and is formed with an opening 82^a.

The head 61 of the adjusting member 26 is secured to and transversely of the lower face of desk 23 in proximity to a side edge of the latter and for such purpose the desk 23 has secured to its lower face in proximity and parallel to its rear edge an angle bar 83 formed of a horizontal flange 84 and a vertical flange 85 depending from flange 84. The latter is anchored against the lower face of desk 23 by the holdfast means 85^a. When head 61 is positioned in relation to desk 23, the angle bar 83 extends through the gullet 70, the arms 80, 81 are arranged against the rear face of flange 85 and against the lower face of flange 84, the arm 69 bears against the lower face of desk 23, the major portion of the length of part 63 of head 61 bears against the lower face of desk 23 and a portion of the upper end of the flanged web 68 is spaced from the lower face of desk 23. The arm 69 is anchored to desk 23 by the holdfast means 86. The arms 80, 81 are secured to the flange 84 by the holdfast means 87, 88 respectively. The means 87 extends through the opening 82^a in arm 80 and also through an opening 89 in flange 85. The means 88 extends through the slot 82 in the arm 81 and through an opening (not shown) in flange 85. The latter may be formed with openings 90 which are to align with the slot 82 in arm 80 for the passage of additional holdfast means if desired. When members 26 are secured to the desk 23, they will appear as shown in Figure 3. The adjusting member 26 is also what may be termed a combined carrier and support for desk 23. Threadedly engaging with the walls of openings 79 is a pair of inwardly extending screws 90^a 40 which function to tighten down member 25 after being adjusted. The member 26 is manually adjusted upwardly and downwardly. The member 26 at the lower end of its rear or inner side is 45 provided with a nose or protuberance 90^b constituting a fulcrum for a purpose to be referred to.

The carrying, receiving and supporting structure or means 27 (Figures 1, 2, 3, 10, 14, 15, 16 and 20) for the desk adjusting member 26 shown in Figures 1, 2, 3, and 5, or for the desk adjusting member shown in Figure 14 also functions to couple desk 23 or the desk structure shown in Figure 14 with the seat 21 and back 22, as well as acting, in connection with a desk adjusting member, to sustain the desk above the seat 21, as well as in forwardly extended relation with respect to seat 21 and back 22. The means 27 includes an upstanding outwardly opening channel-shaped member 91 for receiving shank 62. The member 91 is formed of an intermediate vertical portion or part 92, an upper portion or part 93 extending at a forward inclination from the portion or part 92 and a lower portion or part 94 (Figure 16) extending inwardly at right angles to the portion 93. The member 91 is formed with a pair of spaced parallel side flanges 95, 96 extending from its lower to its upper end. The portion 93 is of greater length than portions 92, 94 and has its upper end edge 97 inclining downwardly from flange 95 to flange 96 whereby the latter is of less length than flange 95. The member 91 on its outer face at its upper end is formed with a rib 98 (Figure 16) arranged between 75

flanges 95, 96 and flush with edge 97. The flange 96 on its outer side edge at the upper end of the latter is formed with a lug 99 provided with a threaded opening 100. The member 91 is provided on its outer face with a series of parallel spaced ribs 101 between the flanges 95, 96 at the lower part of portion 93. The ribs 101 coact with the inner ends of the screws 90^a for locking shank 62 after screws 90^a have been positioned between a pair of ribs. After the screws 90^a have been positioned between a pair of ribs these latter act to prevent the shank 62 from sliding out of position. The desk is entirely loose when the screws 90^a are backed out, but friction through weight of the desk prevents lowering of the latter. The member 91 above the ribs 101 is formed between flanges 95, 96 with a group of spaced openings 102. The member 91 includes an apertured lug 103 (Figure 20) extended from the inner end of portion 94. The member 91 is provided with an angle-shaped extension 104 (Figures 16 and 20) formed of a vertical leg 105 and a horizontal leg 106. The leg 105 merges into the lower end of flange 96. The leg 106 merges into the inner end of portion 94. The extension 104 is disposed inwardly at right angles with respect to the flange 96 and extends inwardly from the inner end of portion 94. The portion 92 is arranged at the forward part of and extends upwardly from a side edge of seat 21. The portion 94 opposes the lower face of the seat 21.

The means 27 includes an elongated horizontally disposed arm or part 107 which at its forward end is flared and integral with the rear side of the flange 95 in proximity to the upper end of the latter. The rear end of the arm 107 is provided with an inwardly extending apertured lug 108. The arm 107 between its forward end and lug 108 is of angle form to provide an upper horizontal flange 109 and a vertical flange 110 depending from the inner side of flange 109. The lug 108 abuts the rear face of the upstanding part of a member 23 and is anchored to the latter by the holdfast means 111 (Figures 9 and 10). The member 91 is anchored to the chair seat 21 and for such purpose there is anchored, by the holdfast means 112, to the lower face of seat 21 in proximity to the forward edge of the latter an angle bar 113 formed of horizontal flange 114 and a vertical flange 115 depending from the latter. One end terminal portion of bar 113 is offset as at 116 to form a space 117 between a portion of flange 114 and the lower face of seat 21. The portion 94 of member 91 is arranged against the lower face of seat 21 and bears on flange 114. The flange 106 of extension 104 is interposed between flange 114 and seat 21. The flange 105 of extension 104 is arranged to abut the rear face of flange 115. The seat 21, portion 94 of member 91 and flange 114 are secured together by the holdfast means 118. The flanges 106 and 114 are secured together by the holdfast means 119. The lug 103 of member 91 is anchored to seat 21 by a holdfast means 119^a (Figure 14.) Carried by the lug 99 is an inwardly extending adjustable screw 119^b which functions to angularly adjust the shank 62 relative to member 81 on fulcrum 90^b.

70 There is associated with the member 91 and shank 62 a clamping structure for securely retaining the latter in its adjusted position. The said structure includes a frusto-tapered clamping block 120 (Figure 19) which is mounted in shank 62 (Figure 16). The block 120 has its

inner face rabbeted as at 121, 122 to form such face with a rib 123. The block 120 is also formed with a group of spaced screw threaded openings 124. When block 120 is arranged in shank 62 the rear faces of the reduced parts 124^a provided by the rabbets 121, 122 are positioned against the inner faces of flanges 77, 78, the rib 123 extends between the lengthwise free edges 125 of the flanges 77, 78 and the openings 124 are to align with the openings 102 in member 91. The clamping structure also includes a set of clamping bolts 126 which extend through the openings 102 in member 91 and threadedly engage in the openings 124 and provide for the clamping of shank 62 to member 91 whereby the desk will be retained in the position to which it has been adjusted by member 26.

With reference to Figures 14, 17 and 18, a flat one-piece body or element 127 is shown which corresponds in contour to that of body 30. The major portion of element 127 provides a desk 128 and its remaining portion an arm rest 129 in the same manner as is provided by body 30.

That part of element 127 which constitutes the desk 128 provides a closure for the open top of a receptacle 130. Secured to the lower face of the desk 128 transversely of the latter is a pair of spaced parallel oppositely disposed angle strips 131 of like form and each consists of a vertical leg 132 and a horizontal leg 133. The legs 132 of the strips 131 are positioned against the outer side walls of a pair of spaced parallel grooves 134 formed in the lower face of desk 128. The legs 133 of strips 131 are secured against the lower face of desk 128 by the holdfast means 135. Positioned against the inner side walls of the grooves 134 and against the legs 132 of the strips 131, as well as being suitably secured to legs 132 are heads 136 on the upper ends of the angle-shaped leaves 137 of hinge members 138 which depend from and extend forwardly with respect to the lower face of desk 128. The receptacle 130 is of less width and length than that of desk 128 and is so disposed relatively to the latter whereby the desk will be arranged in extended relation with respect to the front, rear and sides of the receptacles. The latter includes a corrugated bottom 139, a rear wall 140, a pair of side walls 141, 142 and a front wall 143. The walls 140, 143 are disposed in parallel relation and incline rearwardly from their lower to the upper ends. The side walls 141, 142 at their upper ends are formed with oppositely extending outwardly directed flat flanges 144, 145 disposed at right angles thereto. The forward portions 146 of the side walls are extended above rear portions 147. The forward portions 146 are for the purpose of abutting the lower face of desk 128 to provide for the rear portions 147 to be spaced from said lower face thereby providing a clearance for the flanges 132 when the receptacle is closed by the desk. The flanges 144, 145 are extended rearwardly with respect to the upper end of wall 140, as at 148 to form supports for the cushioning buttons 149 anchored to the lower face of desk 128. Only one extension 148 and one button 149 is shown. The extensions 148 act to support the buttons when the receptacle is closed by desk 128. The lower ends of the buttons align with the tops of the portions 146. The inner faces of the walls 141, 142 in proximity to said forward ends and substantially at the longitudinal medians thereof are formed with internally threaded studs or spacers 150 which are arranged in pairs. Each side wall is formed with 75

a pair of horizontally aligned spaced studs 150. Positioned against the inner ends of each pair of studs 150 is the lower end of an upstanding apertured stationary hinge member 151. The latter is anchored to its associated studs by the holdfast means 152. The outer ends of the members 138 are apertured and these latter align with the apertures of the members 151. The apertures in members 151 are arranged in proximity to their upper ends. The outer ends of the members 138 are interposed between the side walls of the receptacle 130 and the members 151. Extending through the aligned openings of a member 138 and a member 151, as well as being suitably connected to such members is a pivot 153. The members 138, 152 and pivots 153 provide a pair of hinge structures between the desk 128 and receptacle 130. To open the latter, the desk 128 is elevated upwardly from its rear. The pivots 153 extend through the side walls 141, 142 and consist of inwardly extending oppositely disposed headed bolts carrying retaining nuts on their inner ends. The side walls 141, 142 are inwardly flanged at their front ends, rear ends and lower ends. The front and rear walls and the bottom are formed of one piece of material arranged between the side walls, bear against the inner faces of and are suitably secured to the inwardly extending flanges on the side walls. The bottom 147 is formed with one or more openings 154.

An adjusting member common to and for bodily adjusting desk 128 and receptacle 130 in unison is indicated at 155. The member 155 functions for the same purpose as that of member 26. The member 155 depends from and is disposed at an inclination with respect to the back of receptacle 130. The member 155 corresponds in construction to the shank 62 of member 26. The member 155 has its upper end inclining downwardly and forwardly from the upper end of the rear side to the upper end of the forward side thereof. The upper end edge or upper wall of the member 155 is integral with the outer face of the inturned flange at the rear end of one of the side walls of receptacle 130. The member 155 coacts with the means 27 in the same manner as the member 26 does. The member 155 is to have associated therewith the clamping-block 120 and the clamping screws 126.

With reference to Figure 21, it illustrates a modified form of adjusting member 156, an open top book box 157, a modified construction of carrying, receiving and supporting means 158 for the member 156 and a combined desk and arm rest element 159 anchored to the member 156. The latter includes a head 160 corresponding in form and arrangement with respect to element 159 as the head 61 of adjusting member 26. The member 156 also includes a shank 161 of the same form and arrangement with respect to the head 160 as is the shank 62 with respect to the head 61 of member 26. The outer wall of shank 161 at its lower end has threaded openings 162 which correspond to the openings 79 in shank 62. The shank 161 has associated therewith screws 163 which correspond to the screws 90^a associated with the shank 62, but the screws 163 function differently from the screws 90^a. These latter are adjusted to engage portion 93 of member 91 for the purpose of adjusting shank 62 relative to member 91, whereas the screws 163 although they threadedly engage the walls of opening 162, are employed for adjusting a tightener 164 carried by and extended from the lower

end of the shank 161. The tightener is in the form of an angle-piece and is adapted to engage the member 165 of the means 158 for tightening the shank 161 relative to member 165 of means 158. The tightener 164 functions similarly to that of the screws 90^a. The vertical leg 166 of tightener 164 is formed with spaced openings 167 for the passage of the screws 163. The horizontal leg 168 of tightener 164 is to abut member 165. Otherwise than that as stated, the adjusting member 156 will be the same as member 26.

The carrying, receiving and supporting means 158 for the adjusting member 156 is of the same form and arrangement as that of the means 27 heretofore referred to with this exception that the upper end terminal portion of the member 165 of the means 158 has its rear face formed with a transversely extending narrow enlargement 169 formed with spaced threaded openings 170 with which are connected binding screws 171 which bear against the flanges 172, 173 of shank 161.

The box 157 is of the same construction as the open top box disclosed in my co-pending application as aforesaid. The inner wall 174 of box 157 is connected to a side of the chair back 175 as at 176. The wall 174 is also connected with the vertical flange 177 of arm 178 of the means 158 by a hanger 179. The chair seat is indicated at 180 and to which the lower end of the means 158 is anchored.

The arrangement of clamping means heretofore referred to in connection with shank 62 and member 91 is employed for clamping shank 161 and member 165 together after the latter has been adjusted.

With respect to the form including an open top book box closed by the desk, the screws carried by the adjusting member and the means 26 are adjusted to produce a perfect alignment of the desk. Should a student suddenly sit down on any corner of the desk and exercise a strain beyond that which the casting or adjusting member was intended for, a bend would be produced in the latter. Formerly, when such bends occurred the casting was bent back by main force or was exchanged by the factory. This objection relative to the bending back of or substituting a new casting is overcome by the screws referred to which may be adjusted to maintain a proper alignment at all times of the desk and book box, keeping the box square with the level of the seat. The foregoing statement relative to the screw adjustment with a desk is employed alone and not as a closure for a book box.

The invention provides whereby when the desk of the form shown, is loosened, it is level and can be shifted to any position which solves a schoolroom problem requiring that the desk should be level when loosened. This condition means that the desk can be locked or can be left loose for students' requirements. In other words, if five or six students are using the desk during the day, they can make the adjustment of the top quickly without resorting at all to the screws. The leverage of the desk top is such that friction tends to keep it up. In other words, the structural arrangement is such that the desk is constantly remaining level which creates a situation whereby the desk remains fixed without its being locked.

With reference to Figures 27 and 28, a book box or receptacle is indicated at 180 and is of the same form as the receptacle 130 shown in Figure 14, with this exception that the top of receptacle 180 is partly closed at its forward end by a narrow

closure strip 181 having its edge 182 beveled. The structure shown in Figures 27 and 28 includes a combined desk and arm rest element formed from a one-piece flat body 183 having the 5 major portion of its length of greater width and length than its remaining portion. The major portion of body 183 indicated at 184 constitutes the desk and the said remaining portion of body 183 indicated at 185 constitutes the arm rest. 10 The edge 186 of the portion 184 is beveled. The edge 186 coacts with the bevelled edge 182 to provide for the elevation and lowering of body 183 from the rear of the latter. The portion 184 is hinged, as at 187, to the box 180 in the same 15 manner as shown in Figures 17 and 18 with respect to body 127 and box or receptacle 130.

The strip 181 forms a forward flat continuation of the desk provided by the portion 184 when body 183 is in closure position with respect 20 to the top of box 180. The strip 181 may, if desired, have its upper face formed with a groove, not shown, for receiving writing implements.

The chair and pedestal constitutes what may be termed the basic part of the unit. The chair 25 is adapted to have detachably and adjustably connected therewith any one of the forms of the combined desk and arm rest elements, whether the element be provided with a book box or not, thereby providing for the substitution 30 of a different element for the one in connected position and under such conditions interchangeability is provided with respect to such elements.

The shank which carries the desk or the box 35 closed by the desk is constantly tilted outward by the actual weight of the desk, with or without the book box. There is so much weight at the top of the shank that the latter is always at its extreme point. The two set screws with the 40 adjusting clamp at the outside merely serve to tighten the hang of the desk, with or without the box, in that position. The desk with or without the book box remains in a fixed position whether it is locked or not; the locking of the 45 desk is to prevent any loosening of the desk by the student.

What I claim is:

1. In an article of furniture for the purpose set forth, a one-piece flat body formed of an enlarged part and a reduced part extended rearwardly from the latter, said enlarged part providing a desk and said reduced part constituting an arm rest, an angle bar anchored to the lower face of the desk and including a vertical flange, an upwardly and downwardly movable combined adjusting and supporting means for the desk including a head part and a depending rearwardly inclined shank, said head part being secured to the lower face of the desk at right angles to and formed with a gullet for the passage of said bar, said head provided with a pair of oppositely extending arms secured to said vertical flange, and a stationary combined carrying, receiving and supporting structure for said means including a forwardly inclined channel-shaped portion in which said shank is slidably mounted, and a clamping device having a part mounted in said shank and a plurality of elements carried by said portion and coacting with 70 said part for clamping the shank stationary to said portion.

2. In an article of furniture for the purpose set forth, a one-piece flat body formed of an enlarged part and a reduced part extended rearwardly from the latter, said enlarged part pro-

viding a desk and said reduced part constituting an arm rest, an angle bar anchored to the lower face of the desk and including a vertical flange, an upwardly and downwardly movable combined adjusting and supporting means for the desk 5 including a head part and a depending rearwardly inclined shank, said head part being secured to the lower face of the desk at right angles to and formed with a gullet for the passage of said bar, said head provided with a pair 10 of oppositely extending arms secured to said vertical flange, a stationary combined carrying, receiving and supporting structure for said means including a forwardly inclined channel-shaped portion in which said shank is slidably mounted, 15 said portion and shank having correlated parts for selectively tilting said shank in directions at right angles within said portion, and a clamping device having a part mounted in said shank and parts carried by said portion for clamping the 20 shank stationary to said portion when the shank is adjusted and non-adjusted.

3. The invention as set forth in claim 1 having said shank of rectangular cross section and hollow, said shank being closed at its top, front and 25 sides, open at its bottom and having its back split lengthwise, the said part of said clamping device being in the form of a block having a portion arranged in the shank and a portion positioned between the edges of the split of said back, 30 and said elements in the form of clamping screws engaging in the block.

4. In a combined arm rest and receptacle for an article of furniture including front, rear, and side walls, a bottom and an open top, a narrow 35 stationary strip located at the forward portion of said top permanently closing the same, a unitary flat body providing a desk and an arm rest and providing a closure for the top portion of said top, hinged connections secured to the desk 40 and extending downwardly and forwardly from the desk into said receptacle to below said strip, the forward ends of said hinged connections being pivotally connected with said side walls, and said strip having its rear edge beveled, said desk having its forward edge beveled, said bevels being so related to permit of the elevating of the desk to open the receptacle and to form an inclined joint between the strip and desk when the latter is in closing position relative to said 50 top and to provide for the strip forming a flat forward continuation of said desk when the receptacle is closed.

5. An article of furniture comprising a chair having its back extending rearwardly at an inclination from bottom to top and its seat extending at an upward inclination from rear to front, a desk arranged over, extending forwardly from and disposed in transverse relation with respect to said seat, a head secured to the desk 60 for supporting it, an upstanding hollow shank merging at its upper end into said head, a supporting structure having an upstanding part arranged at one side of the forward portion of the seat, a horizontal part integral with and extending rearwardly from the rear side of said upstanding part and an angle-shaped part below and merging into the bottom of the upstanding part, said horizontal and angle-shaped parts being secured respectively to said back and seat 65 on the same side of the chair, said upstanding part being of channel-shaped form and in which said shank is slidably and adjustably mounted, said structure including adjustable means carried by said upstanding part and extending in and 70 75

coating with said shank for clamping the latter stationary to said upstanding part.

6. The invention as set forth in claim 5 having said shank disposed at a rearward inclination relative to said head, said upstanding part being disposed at an inclination corresponding substantially to the inclination of said shank, and said angle-shaped part having a portion vertically disposed and merging into said upstanding part.

7. The invention as set forth in claim 5 having said angle-shaped part formed with a portion vertically disposed, said upstanding part extending at an inward inclination with respect to said vertical portion, and said shank being disposed at an inclination corresponding to the inclination of said upstanding part.

8. The invention as set forth in claim 5 having said shank and upstanding part formed with adjustable abutting means for selectively tilting the shank in different directions with respect to said upstanding part.

9. An article of furniture comprising a chair including a back and a seat, a desk arranged over, extending forwardly from and disposed in transverse relation with respect to the seat, said desk being formed with a rearwardly extending arm rest, a head secured to the desk for supporting it, an upstanding forwardly inclined hollow shank merging at its upper end into the head for supporting and vertically adjusting it, said shank being formed on its inner side with a slot, and a shank receiving, carrying and supporting structure including an upstanding forwardly inclined channel-shaped part in which the shank is slidably mounted and adjusted relative thereto, said part being arranged at the forward portion of one side of the chair and terminating at its lower end into an angle-shaped part arranged against and secured to the lower face of said seat, said structure including a horizontally disposed bracing portion integral with and extending rearwardly from the rear side of said channel-shaped portion and being secured to the back of the chair at the said side of the latter, a clamping member arranged within said shank, and adjusting bolts for said member carried by said channel-shaped part and engaging said member, said bolts when adjusted in one direction providing for said clamping member binding against the inner face of and extending into the slot of the shank whereby the latter will be clamped stationary, in its normal and adjusted position, to said structure.

10. An article of furniture comprising a chair including a back and a seat, a desk arranged over, extending forwardly from and disposed in transverse relation with respect to the seat, said desk being formed with a rearwardly extending arm rest, a head secured to the desk for supporting it, an upstanding hollow shank merging at its upper end into the head, and a shank receiving, carrying and supporting structure including an upstanding channel-shaped part in which the shank is slidably mounted and adjusted relative thereto, said part being arranged at one side of the chair and provided at its lower end with an inwardly extending portion arranged against and secured to the lower face of the seat, said structure including a bracing portion integral with and extending rearwardly from the inner side of said channel-shaped part and being se-

cured to the back of the chair at the said side of the latter, an adjustable clamping means carried by said channel-shaped part, extending into and correlated with said shank for clamping the latter in its normal and adjusted position stationary to the said structure.

11. The invention as set forth in claim 10 having said shank provided on its rear side with a lateral protuberance bearing against the rear side of said channel-shaped part and constituting a fulcrum to provide for the shank shifting at an angle relative to said channel-shaped part, and said channel-shaped part including adjustable means on the front side thereof and bearing against the front side of the shank for shifting and retaining the latter in its adjusted angular position.

12. The invention as set forth in claim 10 having the lower end of said shank provided with adjustable means bearing against the front face of said channel-shaped part for disposing the shank in angular relation with respect to said channel-shaped part.

13. An article of furniture comprising a chair including a back and a seat, a desk arranged over and extending forwardly from the seat, a head secured to the desk for supporting it, an upstanding shank merging at its upper end into the head, a shank receiving, carrying and supporting structure including an upstanding part in which the shank is slidably mounted and adjusted relative thereto, said part being arranged at one side of the chair and provided at its lower end with an inwardly extending portion secured to the seat, said structure including a bracing portion extending rearwardly from said upstanding part and being secured to the back of the chair, an adjustable clamping means carried by said upstanding part, extending into and correlated with said shank for clamping the latter in its normal and adjusted positions, said shank provided on one side with a lateral protuberance bearing against one side of said upstanding part and constituting a fulcrum to provide for the shank shifting at an angle to said upstanding part, and said upstanding part including adjustable means on the other side thereof and bearing against the other side of the shank for shifting and retaining the latter in its adjusted angular position.

14. An article of furniture comprising a chair including a back and a seat, a desk arranged over and extending forwardly from the seat, a head secured to the desk for supporting it, an upstanding shank merging at its upper end into the head, a shank receiving, carrying and supporting structure including an upstanding part in which the shank is slidably mounted and adjusted relative thereto, said part being arranged at one side of the chair and provided at its lower end with an inwardly extending portion secured to the seat, said structure including a bracing portion extending rearwardly from said upstanding part and being secured to the back of the chair, an adjustable clamping means carried by said upstanding part, extending into and correlated with said shank for clamping the latter in its normal and adjusted positions, and said shank having its lower end provided with adjustable means bearing against one face of said upstanding part for disposing the shank in angular relation with respect to said upstanding part.

WILLIAM J. BARGEN.
